(57) **CLAIM**

The ornamental design for a single device electrical junction box with side door, as shown and described.

DESCRIPTION

FIG. 1 is a front perspective view of a single device electrical junction box with side door;

FIG. 2 is a top plan view thereof;

FIG. 3 is a bottom plan view thereof;

FIG. 4 is a front elevation view thereof;

FIG. 5 is a rear elevation view thereof;

FIG. 6 is a right-side elevation view thereof;

FIG. 7 is a left-side elevation view thereof;

FIG. 8 is a front perspective view thereof, shown in a first alternate position;

FIG. 9 is a front perspective view thereof;

FIG. 10 is a rear perspective view thereof, shown in the first alternate position;

FIG. 11 is a front perspective view thereof, shown in a second alternate position; and,

FIG. 12 is a rear perspective view thereof, shown in the second alternate position.

The dash-dash broken lines represent portions of the single device electrical junction box with side door that form no part of the claimed design.
